CLAIM

The ornamental design for a cable hole cover, as shown and described.

DESCRIPTION

FIG. 1 is an exploded front elevation view of a cable hole cover showing the new design;

FIG. 2 is an exploded back elevation view thereof;

FIG. 3 is an exploded left-side view thereof;

FIG. 4 is an exploded right-side view thereof;

FIG. 5 is an exploded top plan view thereof;

FIG. 6 is an exploded bottom plan view thereof;

FIG. 7 is an exploded perspective view thereof;

FIG. 8 is another exploded perspective view thereof;

FIG. 9 is a perspective view thereof; and,

FIG. 10 is another perspective view thereof.

1 Claim, 10 Drawing Sheets
